UNITED STATES PATENT OFFICE.

NATHAN I. BERGER, OF NEW YORK, N. Y.

ADJUSTABLE ELECTRIC FIXTURE.

1,171,831.

Specification of Letters Patent. Patented Feb. 15, 1916.

Application filed June 5, 1915. Serial No. 32,295.

To all whom it may concern:

Be it known that I, NATHAN I. BERGER, a citizen of the United States, residing in the city, county, and State of New York, have 5 invented certain new and useful Improvements in Adjustable Electric Fixtures, of which the following is a specification.

This invention relates to an adjustable electrolier, the object being to provide such 10 an article, or a chandelier, arranged to retain globes of various diameters.

To carry my invention into practice, I form the shade support out of a plurality of pivotally connected members to which is 15 suitably secured a yieldable band which in turn constitutes a rim upon which the globe can rest.

In the drawing, which forms part of this specification, Figure 1, is a side elevation of 20 my improved device; Fig. 2 is a sectional plan view, the section being taken on a line 2—2 in Fig. 1; Fig. 3 is an enlarged sectional detail view, the section being taken on a line 3—3, Fig. 1.

As herein illustrated, my invention consists of a chandelier, or an electrolier, indicated by 1, consisting of ceiling fixture 2, from which is suspended a frame 3, to which is pivotally secured at 4 a plurality of members 5. To the lower end of said members I secure a yieldable annular rim 6 consisting in this instance of a coil spring upon which a globe 7 can be suspended. The spring or rim 6 can be secured to the members 5 in any 35 desirable manner, such for instance as by staples 8.

By virtue of the action of the spring 6 the globe 7 will be tightly gripped and held in position. Moreover, the said yieldable rim 40 or spring 6 will serve to retain globes of various diameters as it is capable of being increased or decreased in diameter. Should I desire to remove the globe 7 for cleaning, or for the substitution of another, I would 45 spread the members 5, at their lower ends, moving them upon their pivots 4, which action would draw the yieldable rim 6 away from the globe 7, permitting said globe to be removed. Should the substituted globe 50 be smaller in diameter, the yieldable rim 6 would contract until it contacted with the

inserted globe. The same action would take place should the substituted globe be larger in diameter. In other words, the yieldable rim 6 will accommodate itself to the diameter of the globe to be held, the pivotal members 5 being arranged to swing inwardly or outwardly. The movement outwardly will be accomplished manually, the movement inwardly will be accomplished by the action of the spring or rim 6.

The device may be made up as elaborate as desirable. Electric bulbs or other means of illumination have not been shown, but it will be understood that such will be used in connection with my device.

What I claim is:

1. An adjustable fixture, or the like, consisting of a frame, a plurality of members radially adjustably secured to said frame, 70 and an adjustable yieldable rim carried by said frame arranged to retain globes of various diameters.

2. An adjustable fixture, or the like, consisting of a frame, a plurality of arms pivotally secured at one end thereof to said frame, and a yieldable rim secured to said arms at the free ends thereof.

3. An adjustable fixture, or the like, consisting of a frame, a plurality of arms pivotally secured at one end thereof to said frame, and a yieldable rim consisting of a coil spring carried by said arms at the free ends thereof, said spring being secured to said arms.

4. An adjustable fixture consisting of a permanently secured frame, a plurality of arms pivotally secured at one end thereof to said frame and arranged to be freely moved upon their pivotal points, and a continuous coil spring secured to said arms at their free ends, said spring being unsupported intermediate said arms and arranged to support a globe.

Signed at the city of New York, New York, this 26th day of May, one thousand nine hundred and fifteen.

NATHAN I. BERGER.
